UNITED STATES PATENT OFFICE

FRANK J. ABEL, OF NEW YORK, N. Y., ASSIGNOR TO SUN RISE LAMP MFG. CO. INC., A CORPORATION OF NEW YORK

DESIGN FOR A PLATE FOR SMOKERS' STANDS

Application filed August 30, 1930. Serial No. 36,834. Term of patent 3½ years.

To all whom it may concern:

Be it known that I, FRANK J. ABEL, a citizen of the United States of America, and a resident of the city of New York, in the county of Bronx and State of New York, have invented a new, original, and ornamental Design for a Plate for Smokers' Stands, of which the following is a specification, reference being had to the accompanying drawing, forming a part hereof.

The single figure shows a perspective view of the plate for smokers' stands.

I claim:

The ornamental design for a plate for smokers' stands substantially as shown.

FRANK J. ABEL.
